US00D521380S

(12) United States Design Patent (10) Patent No.: US D521,380 S
Jackson et al. (45) Date of Patent: * May 23, 2006

(54) COVER FOR A FOOD PACKAGE

(75) Inventors: Daniel C. Jackson, Plymouth, MN (US); Nicolas Bouveret, St-Placide (CA); Jean-Pierre Lacroix, Bois d'Amont (FR)

(73) Assignee: Land O'Lakes, Inc., Arden Hills, MN (US)

() Term: 14 Years

(21) Appl. No.: 29/208,195

(22) Filed: Jun. 24, 2004

Related U.S. Application Data

(62) Division of application No. 29/193,960, filed on Nov. 17, 2003, now Pat. No. Des. 496,272, which is a division of application No. 29/165,907, filed on Aug. 20, 2002, now Pat. No. Des. 489,975.

(51) LOC (8) Cl. 09-07

(52) U.S. Cl. D9/435; D9/425

(57) CLAIM

The ornamental design for a cover for a food package, as shown and described.

DESCRIPTION

FIG. 1 is a perspective view of a cover for a food package of the present invention;

FIG. 2 is a top plan view of the cover;

FIG. 3 is a front elevational view of the cover;

FIG. 4 is a right side elevational view of the cover;

FIG. 5 is a rear elevational view of the cover;

FIG. 6 is a left side elevational view of the cover; and,

FIG. 7 is a bottom plan view of the cover.
